D.B. Moore

Sawing Shingles.

Patented Aug. 15, 1835.

Aug. 15, 1835 8998X 41.

David B. Moore of Gilmanston New Hampshire
Letters Patent.

The Schedule referred to in these Letters Patent and making part
of the same, containing a description in the words of the said
David B. Moore himself of his improvement in a machine for
sawing Shingles.

To all to whom these presents shall come: Be it known
that I David B. Moore of Gilmanston in the County of Strafford,
and State of New Hampshire, have invented a new and useful
improvement in the mode of sawing Shingles, which I have adap-
ted to Carl's Patented Shingle machine, and claim it as an im-
provement thereon, and the following is a full and exact descrip-
tion of the construction and operation of the said machine as
invented or improved by me. The object of my improvement is
to produce such an arrangement of machinery as will prevent
the bolt or piece of wood, from which the shingles are to be cut, &
the operation of the saw in a much more simple and efficacious
manner than heretofore, and which I proceed to set forth and de-
scribe, by reference to the drawings which accompany this Spec-
ification, after the following method, which moves the bolt
in towards the saw, and confines firmly in its place, one end
thereof, while the carriage returns, and moves inwards the other
end, thus. A represents the head stock, which slides hori-
zontally between the two transverse beams B. C. of the carriage
D. The motion of this head stock is regulated by means
of a set plate E. at each end and which consists of a
thin flat bar of iron perforated with holes at about the
distance of the thickness of the butt of a shingle, and having
the upper edge formed into teeth. At the same distance
apart, as the holes and pointing from the head stock.
These set plates are made firm to the underside of the

head stock and slide at right angles thereto, one along the hinder side of the hinder transverse beam B. and the other upon the hinder side of the forward transverse beam C. upon the top of each of these beams B. & C is fixed an arm or fall F which falls into each notch as the slide set plate E advances and holds it secure from any tremulous motion backwards lest the pointer should miss the hole as described hereafter. A tongue G. and groove H. is fastened at the forward side of each beam B. & C. to assist in guiding the head stock A. Two mortises are cut through the end of each transverse beam for the reception of the pointing rods I. J. which play forward and backward therein under the set plates E. and project beyond these beams about six inches at the front and at the hinder ends, in size they will be about two inches by about three quarters of an inch. Upon the tops of these rods are placed the pointers K. which are two cylindrical pieces of iron pointed of about three inches in length, by about one third of an inch in diameter each being intended to project forwards into a button or piece of wood L about one inch high, one to be placed behind the hinder set plate and the other behind the forward set plate. The button works, or turns upon a pin in its hinder part driven into the pointing rod and has behind it a small spring M bearing against the hinder end of the button, in such a manner as to constantly bear the opposite or pointed end K in a direction leading from the head stock, or outwards from the saw, in which direction it flies until arrested by means of a small pin or guard N. and this distance at which it is arrested is such as always to stop the point opposite to the hole in the set plate that it is to enter. And here the arm or fall is of use as it prevents any possibility of the set plate sliding too far back by the trembling of the machine to prevent any other than the proper hole or distance to the pointer. When the carriage D moves backwards, the pointing rod J whose pointer is disengaged, is forced against a head block O. which is secured in an upright position and the back part of the top of the longitudinal beam of the frame, and thrust at once into the opening left in the end

of each transverse beam for that purpose and which forms an inclined plane, rising or advancing inwards towards the saw and is lined with metal so that the moment the pointer enters the hole 2, it is forced to slide or thrust up this plane, coming in contact with the metal and continues up until it arrives at a long hole 3, continues forwards in a straight line at the top of this inclined plane, into which it enters and there remains holding the set plate firm until it is withdrawn when the other pointer is to enter its hole and so alternately. The length of this inclined plane is to be adjusted to the length or distance of the holes apart, so that there shall be no impediment to entering the next hole at the return of the pointer by which means the setting plate and head stock is advanced each time the distance of a hole. The head stock is formed to be double over or shut down by means of a hinge P, so as to present only so much in height as will allow the pointing rods to pass over it when it is necessary to put in a new bolt a recommends sawing. It remains to show or describe the arrangement by which is given the alternate play to the two pointing rods, which their fixtures so that by means of the set plates & the head block is made to approach nearer to the saw. A rod which I call a slipper rod Q is attached to the lower end of the forward transverse beam, by means of a pin passing through the said beam and secured at the top side thereof by a pin or other means, and this pin is attached by means of a swivel joint R, also acting as an up and down hinge joint, and the forward end of the slipper rod. This pin is passed through the transverse beam, just between the pointing rods. The slipper rod extends from the forward beam to the hinder one where its end is reduced to a rounded edge S, for the purpose of sliding past the shifting rods, and its underside T, is also reduced to a long pointed shape, as will be best explained by reference to the drawing intended to slide past the pointed joint of the shifting rods on its advancing, forwards which it does by being tracked after the forward transverse beam and upon the longitudinal beam of the frame by means of the pin and swivel joint. There are two pins S inserted into the lower

side of the hinder transverse beam, directly under the mortise through which the pointing rods slide, and are intended to secure the shifting rod in its position when passing the triangular end of the shifting rod. Rest the shifting rod, and upon the longitudinal beam I place the shifting rods T. M. connected by the joint V. and working or moving upon the pivot W. let into the longitudinal beam. These shifting rods extend from the hinder beam to some distance before the forward beam (the pivot of the shifting rod U being situated about a little in advance of the forward beam) and at this forward end an upright pin X is placed of sufficient height to reach to or touch either one or the other of the pointing rods as they may be presented in front of the forward beam, which causes that pointing rod to recede and consequently to carry back or disengage its pointer; when by the return of the carriage the next pointing rod presents itself to the pin X and has its pointer disengaged in like manner. This alternate presentation is effected by means of the formation of the hinder or triangular end T. of the shifting rod (the shape of which is best understood by the drawing) which being movable upon the joint V thereof and turning ^{up} on its pivot W. when the end of the shifting rod L. slides backwards and forwards over the space between (the dotted lines in the drawing) the joint V and the pivot W. of the triangular rod T. This distance and the width of the triangular rod is so adjusted that at each passage of the shifting rod between the said triangular end and the pin X which is immovable, the triangular end T must turn on its pivot and consequently give a contrary direction to the joint V. which again brings the forward end with the pin X to turn to the same side as the triangular end T. and this motion alternates so as to bring the pin X first to one pointing rod and then to the other, by which means the respective pointers are disengaged on one bar and thrust in on the other so as to advance the setting plates alternately and consequently the bolt from which the shingle is to be cut by which the butt and thin edge of the shingle is formed. The carriage runs back after the cut is made by means of a weight attached to it.

running on a pulley behind. What I claim as my invention and not before known in the above described machine is the arrangement or combination by which I produce the alternate motion that presents first one end of the other of the bolt or wood to be sawed; but I do not claim that motion it having been used before but simply the means by which I effect it and which consists of the following parts, viz 1st. The set plates C as formed and applied according to the description with the application of the arm or pull, for the use described 2dly. The pointing rods and pointers as set forth. 3dly. the head block used as above. 4thly. the manner in which I shape and use the shiffee rod. 5thly. the shape and formation of the shifting rods.

In testimony that the above is a full and exact description of the construction and mode of operation of my machine as invented or improved by me. I have hereunto set my hand this first day of June eighteen hundred and thirty five
